UNITED STATES PATENT OFFICE.

FELIKS RUSIN, OF CHICAGO, ILLINOIS.

CHILD'S SWING AND CRADLE.

1,177,575.

Specification of Letters Patent. Patented Mar. 28, 1916.

Application filed July 2, 1913. Serial No. 776,915.

To all whom it may concern:

Be it known that I, FELIKS RUSIN, a subject of the Emperor of Austria-Hungary, residing at Chicago, in the county of Cook 5 and State of Illinois, have invented certain new and useful Improvements in Children's Swings and Cradles, of which the following is a specification.

My invention relates to a combination 10 swing and cradle and has particular reference to improvements for putting this idea into practicable form adapted for actual use in a home.

The object of the invention is to provide 15 a pair of chairs which may be suitably combined into a practical form of cradle, mount these chairs on a swinging platform itself mounted on rockers, and to provide means in connection with the above whereby a 20 child or two children may swing themselves and thus relieve the parent of the duty of devoting its time to the child while it is amusing itself in this manner.

With these objects in view my invention 25 consists in the novel construction, combination and arrangement of parts, all as hereinafter described in detail, illustrated in the accompanying drawing and incorporated in the appended claim.

30 In the drawing—Figure 1 is a perspective view of a device embodying my invention, showing the chairs arranged as a swing. Fig. 2 is a similar view in changed position showing the chairs arranged as a cradle.

35 In the several views 2 and 3 represent rockers from which rise posts 4, 5, 6, and 7 suitably braced as by braces 8, 9, 10 and 11. These rockers are connected by cross-bars 12, 13 and 14. From the posts a platform 40 15 is suspended on cords or suitable flexible connections 16, 17, 18 and 19 which are secured in any suitable manner near the corners of said platform 15. On the platform is mounted a pair of chairs 20 and 21 45 of such construction as to adapt them for combination into a neat and ornamental cradle, the chairs' arm-rests 22, 23, 24, and 25 being for this purpose provided with forward supports 26, 27, 28 and 29 which

are gracefully curved and inclined to provide sides for the cradle of the open work type but forming sufficient side closure to prevent a child from falling out from under the arms of the chair. The chairs are held in place on the platform by means of pins 50 30 which project from the front legs 31 and 32 and engage holes 33 and 34 in the platform. The holes 33 space the chairs apart for their chair swing positions, while the holes 34 are used to hold the chairs in their 55 cradle positions. Midway between the chairs in their swing position of Fig. 1 is arranged a vertical lever 35 which is fulcrumed in an oblong hole 36 in the platform and has its lower end pivoted at 37 to 60 the cross-rod 13. On the upper end of this lever is a foot rest 38 which is conveniently arranged for the child's or children's feet either as a rest for the feet or as a means of propelling the mechanism as a swing. 65

I am aware that mounting a cradle or chairs on a platform supported by flexible connections so that said cradle or chairs may be swung to or fro or sidewise or in 70 a circle is not in itself novel, and no claim is 75 therefore made for this feature alone.

Having thus described my invention, I claim as new and desire to secure by Letters Patent—

The combination with the supporting 80 frame mounted for swinging movement, of the platform 15 flexibly mounted on said frame to swing at right angles to the swinging motion of said frame, chairs mounted on said platform, means supporting said 85 chairs against accidental movement relative to each other, a foot-rest, a lever on said foot-rest pivoted to said platform and a fulcrum support for said lever underneath said platform. 90

In testimony whereof I have hereunto set my hand in the presence of two subscribing witnesses.

FELIKS RUSIN.

Witnesses:

FRANK PECZAK,
JOSEP HERCIK.
